United States Patent Office.

MAJOR H. FISHER, OF BRIDGEPORT, CONNECTICUT.

Letters Patent No. 79,461, dated June 30, 1868.

IMPROVED MACHINE FOR MAKING RASPS.

The Schedule referred to in these Letters Patent and making part of the same.

TO ALL WHOM IT MAY CONCERN:

Be it known that I, MAJOR H. FISHER, of Bridgeport, in the county of Fairfield, and State of Connecticut, have invented a new Improvement in Machine for Making Rasps; and I do hereby declare the following, when taken in connection with the accompanying drawings, and the letters of reference marked thereon, to be a full, clear, and exact description of the same, and which said drawings constitute part of this specification, and represent, in—

Figure 1, a side view,

Figure 2 a top view,

Figure 3 a face view,

Figure 4 an edge view of the principal cam,

Figure 5, a detached sectional view of the cutter and its connection, and in

Figure 6 a face view of an ordinary rasp.

This invention is designed for cutting common rasps, such as are used by horse-shoers and others, and consists—

First, in the arrangement of the cutter upon its holder, so that while it is held firmly, it is allowed to turn up at its point as it enters the steel, so as to throw up the tooth of the rasp.

Second, in hanging the tool-holder at a point one side from the centre of the traverse of the cutter, so as to make the traverse of the cutter to advance as it proceeds across the rasp.

Third, in the arrangement of a cam, in combination with the cutter-holder, so as to cause it to intermittently move across the rasp-blank, so as to raise the teeth at the proper point, and the requisite number of teeth in the different rows, that is to say, one more tooth in each alternate row than there is in the immediate preceding row; and

Fourth, in imparting to the bed in which the rasp is placed a movement relative to the transverse movement of the cutter, so that the teeth cut will be in rows at right angles to the edge of the rasp.

To enable others to construct and use my improvement, I will proceed to describe the same as illustrated in the accompanying drawings.

In fig. 5 a top view of the rasp is shown, where, it will be seen, there are nine teeth in one row, eight in the next, and so on, alternating nine and eight, or if a greater or less number, always that same variation of one more tooth in one row than there is in the next.

A is the frame of the machine, which supports the operative mechanism; B, the cutter-holder, supported in a shaft, C, the said shaft having its bearings in the frame at c. The said cutter-bar passes through the said shaft, and is pivoted thereon at one side of the centre, at a. D, the cutter, is attached to the holder B, by a stirrup, E, as seen in fig. 5; the said stirrup passing through the mortise s, in the said cutter, and extending back beneath the holder, and so as to support the tool in its proper position, and is held back by a spring, f, the said spring being sufficient to hold the tool firmly in its position, and yet so that when it strikes into the steel, the inclination upon the edge of the cutter tending forward, the cutter will cut under, as denoted in red, and thus turn up the tooth on the rasp. The cutter is removed by releasing the spring which holds it in position.

By hanging the cutter-holder B at the point a, and the point a being at one edge of the rasp, or still farther from the centre line thereof, and the cutter D swinging from that point, it will be seen that the arc described by the centre approaches from the starting-point toward the shaft C; that is to say, that the cutter, passing across the blank, when it reaches the opposite side, is nearer to the shaft C than when it started, but as it is desirable to cut the line of the teeth across the cutter at right angles to the edge of the rasp, it is necessary to give to the blank a movement relatively to the arc described by the cutter, so that the said arc and the said movement will direct the tool to strike the blank in a line at right angles across the face of the blank.

The object, therefore, of hanging the tool-holder at one side is, that this required relative movement of the blank is more easily attained than if the tool be moved in an arc described from a point centrally on the blank. To give this relative movement to the blank, I arrange a screw, F, which is attached to the blank-holder G, and operated from the shaft H, so as to give the required relative movement. The shaft C is operated through an eccentric, I, and a connecting-rod, J, as seen in figs. 1 and 2, to give to the cutter the movement required to strike the blank.

The cutter-holder B extends through the shaft C, and attached to a sliding bar, K. The said sliding bar is operated by a cam, L, the said cam being seen enlarged in figs. 3 and 4. The face of the said cam is divided between the opposite points 1 and 1', so that upon one side there is one less projection than upon the other, so that moving in the direction denoted by the arrow, a notch is cut at 1', another at 2', another at 3', then the slide falls back to the first position seen in fig. 2; then, by the projections 1, 2, 3, and 4, the next row of teeth are cut; then, falling back, the third row of them will be cut, and so on, the number of projections on the cam governing the number of teeth, which must always be one more in one row than in the next.

Having thus fully described my invention, what I claim as new and useful, and desire to secure by Letters Patent is, not the parts hereafter specified in severality, but

1. Attaching the cutter D to the holder B, by means of the stirrup E and spring f, when the said stirrup is arranged to support the cutter, and at the same time to allow the point to turn up, substantially in the manner and for the purpose set forth.

2. In combination with the holder B, arranged and operated as above, I claim the blank-holder G, and mechanism, substantially as described, for imparting to the said holder a movement relatively to the movement of the cutter across the blank, so that the teeth cut in each row shall be at right angles to the edge of the rasp, substantially as herein set forth.

MAJOR H. FISHER.
